STOOL OR CHAIR

Bertis F. Hamilton, Earl F. Hamilton, William S. Hamilton, and Clarence O. Hamilton, Columbus, Ind.

Application February 10, 1941, Serial No. 378,208

8 Claims. (Cl. 155—194)

It is the object of my invention to produce a stool or chair which can be simply and economically manufactured, which can be shipped in knocked-down condition in a compact package, and which can be readily assembled by the retailer or purchaser. A further object of my invention is to produce a stool or chair of the type indicated which, when assembled, will be rigid and sturdy.

In carrying out my invention, I form the stool or chair with a seat provided with a depending peripheral flange having at circumferential intervals provisions for the reception of separate legs. Each leg is formed at its upper end with provisions interfitting with those on the seat-flange and adapted, when the leg is in position, to form a rigid connection holding the leg in fixed position relative to the seat against all movement except a swinging movement in a plane radial with respect to the seat. After the legs have been attached to the seat and the aforesaid provisions interfitted, there is applied to the legs a rigid ring which holds them in fixed position relative to each other and prevents the swinging movement necessary to disengage the provisions interconnecting the legs with the seat-flange.

The accompanying drawing illustrates an embodiment of my invention: Fig. 1 is a front elevation and Fig. 2 a plan view of a stool; Fig. 3 is a section on the line 3—3 of Fig. 1; Fig. 4 is a fragmental plan view of a peripheral portion of the stool-seat; Fig. 5 is a horizontal section on the line 5—5 of Fig. 9; Fig. 6 is a horizontal section on the line 6—6 of Fig. 1; Fig. 7 is a horizontal section on the line 7—7 of Fig. 8 showing the connection between one of the stool-legs and the ring above referred to; Fig. 8 is a fragmental elevation of the parts illustrated in section in Fig. 7; Fig. 9 is a fragmental elevation of the top of one of the legs and the adjacent portion of the seat; and Fig. 10 is a vertical section on the line 10—10 of Fig. 9.

The seat 10 of the preferred embodiment illustrated in the drawing is provided with a depending peripheral flange having an upper portion 11 and a lower portion 12 of larger diameter than the portion 11 and separated therefrom by a step or shoulder 13. The extreme lower edge of the flange-portion 12 is desirably turned inwardly as indicated at 14 for the purpose of improving appearance and strengthening the flange.

At points where legs are to be attached to the seat, the step or shoulder 13 is cut away as indicated at 15 in Fig. 4; and adjacent the sides

5 of the opening 15 the flange-portion 12 is formed to provide two outwardly opening, vertically extending grooves 16. In the stool illustrated in the drawing, the seat 10 is circular and the four legs 20 which support that seat are identical with each other. Each of such legs is desirably formed of sheet-metal in a channel-section, the lower ends of the legs being provided with cushioning tips 21 of rubber or some similar material. At its upper end, the cross-sectional curvature of each leg 20 is gradually reduced until it conforms approximately to the curvature of the flange-portion 12, and the extreme upper end of the leg is offset inwardly as indicated in Fig. 10 to provide a horizontally extending shoulder 23 and a generally vertically extending lip or tongue 24. Immediately below the shoulder 23 the side edges of each leg are turned inwardly to form flanges 25 (Fig. 5) receivable within the grooves 16 in the flange-portion 12.

10 To maintain the lower ends of the legs 20 in fixed relation to each other, I desirably employ a ring formed of two semicircular strips of sheet-metal 30 channel-like in cross-section. One end 15 of each of the semicircular pieces 30 is provided with an inwardly offset tongue 31 which, when the two pieces are brought together to form a circular ring, overlaps the adjacent end of the other piece, as indicated in Fig. 7. The two pieces 25 30 desirably meet at points adjacent diagonally opposite legs 20, and each tongue 31 and the piece it overlaps are provided with alined openings for the reception of a bolt 32 which extends also through the adjacent leg. Where the ring 30 crosses other legs, additional bolts 32 are provided for securing the ring and those additional legs together. Desirably, as will be clear from Fig. 5, 35 the material of each leg is offset inwardly where the ring formed by the two pieces 30 crosses it so as to provide a guiding or locating shoulder for such ring.

40 The stool shown in the drawing is provided with a back 35 desirably formed of sheet-metal and secured as by welding to two sheet-metal supports 36. The lower ends of such supports are secured to the flange 11—12 by bolts 37, as indicated in Fig. 3.

45 I contemplate that the parts of the stool or chair embodying my invention will, as manufactured by the manufacturer, be painted or otherwise finished and shipped in knocked-down condition in a suitable packing case. To erect the device, the legs are successively attached to the seat 10, the ring 30 is secured to the lower ends 50 of the legs, and the back 35—36 then attached.

In bringing each leg into association with the seat, the leg is held approximately co-planar with the seat and the tongue 24 and shoulder 23 are inserted through one of the openings 15 in the shoulder 13, as indicated in dotted lines in Fig. 10. The resulting engagement of the angle between the shoulder 23 and tongue 24 with the inner edge of the opening 15 affords a pivotal connection about which the leg may be swung downwardly relatively to the seat to bring the leg into the position illustrated in full lines in Fig. 10. In this position, the flanges 25 on the leg are received within the grooves 16 in the flange-portion 12, thus preventing any movement of the leg except in a plane parallel to the grooves and flanges. The shoulder 23 engages the lower edge of the flange-portion 11 and the upper edge of the flange-portion 12 at the sides of the opening 15, thus preventing any upward or downward movement of the leg relative to the seat. The tongue 24 at the extreme upper end of the leg engages the inner face of the flange-portion 11 and prevents the upper end of the leg from moving outwardly relative to the seat. When the ring-parts 30 are applied to the lower ends of the legs, the legs are all firmly connected together and the stool is rigidly assembled. Desirably, to take up any looseness or lost motion the tongue 24 is so formed as to engage either the under surface of the seat 10 or the inner surface of the flange 11 shortly before the leg, in its downward swinging movement, reaches the position it is eventually to occupy. This arrangement results in the imposition of a light stress in the leg and prevents any rattling such as would result from looseness. If, as is shown in the drawing, the upper end of the tongue 24 engages the lower surface of the seat it may aid in transmitting to the legs any load applied to the seat.

I claim as my invention:

1. In a stool or chair, a generally horizontal sheet-metal seat provided with a peripheral flange having an upper portion, an outwardly extending intermediate portion forming a shoulder, and a lower portion of larger diameter than said upper portion, said intermediate portion being provided at intervals with leg-receiving openings, the lower portion of said flange being formed at the ends of each of said openings to provide outwardly opening, downwardly extending grooves, a leg for each of said openings, said leg being formed of sheet-metal and having its upper end offset to provide an inwardly extending shoulder engaging the inner edge of the associated opening and a lip engaging the inner surface of the seat, said leg below said shoulder having its edges bent inwardly to form flanges received in said grooves, and a ring disposed near the lower ends of said legs and secured thereto.

2. In a stool or chair, a generally horizontal sheet-metal seat provided with a peripheral flange having an upper portion, an outwardly extending intermediate portion forming a shoulder, and a lower portion of larger diameter than said upper portion, said intermediate portion being provided at intervals with leg-receiving openings, a leg associated with each of said openings, said leg having at its upper end a lip engageable with the inner edge of the opening when the leg is in a position generally co-planar with the seat to provide a pivotal connection about which the leg can be swung downwardly toward a normal,

generally vertical position, said leg and the lower portion of said flange having provisions engageable by such swinging movement of the leg and co-operating when engaged to prevent movement of the leg about a horizontal axis radial of the seat, and a ring secured to the legs near the lower end thereof.

3. In a stool or chair, a generally horizontal sheet-metal seat provided with a peripheral flange having an upper portion, an outwardly extending intermediate portion forming a shoulder, and a lower portion of larger diameter than said upper portion, said intermediate portion being provided at intervals with leg-receiving openings, a leg associated with each of said openings, said leg having at its upper end a lip engageable with the inner edge of the opening when the leg is in a position generally co-planar with the seat to provide a pivotal connection about which the leg can be swung downwardly toward a normal, generally vertical position, said leg and the lower portion of said flange having provisions engageable by such swinging movement of the leg and co-operating when engaged to prevent movement of the leg about a horizontal axis radial of the seat, and means rigidly interconnecting the lower ends of said legs.

4. In a stool or chair, a generally horizontal sheet-metal seat having a downwardly extending peripheral flange having an intermediate horizontal portion, said horizontal flange-portion being provided with a plurality of spaced openings, a leg associated with each of said openings, said leg being formed at its upper end to provide means engageable with one edge of the associated opening to provide a pivotal connection about which the leg may be swung downwardly toward a normal vertical position, said leg and said flange having below the opening provisions engageable by such swinging movement of the leg and co-operating when engaged to prevent movement of the leg about a horizontal axis radial of the seat, and a ring secured to the legs near the lower end thereof.

5. In a stool or chair, a generally horizontal sheet-metal seat having a downwardly extending peripheral flange having a horizontal portion, said horizontal flange-portion being provided with a plurality of spaced openings, a leg associated with each of said openings, said leg being formed at its upper end to provide means engageable with one edge of the associated opening to provide a pivotal connection about which the leg may be swung downwardly toward a normal vertical position, said leg and said flange having vertically extending, interfitting provisions engageable by such swinging movement of the leg and co-operating when engaged to prevent movement of the leg about a horizontal axis radial of the seat, and a ring secured to the legs near the lower end thereof.

6. In a stool or chair, a generally horizontal sheet-metal seat having a downwardly extending peripheral flange having a horizontal portion, said horizontal flange-portion being provided with a plurality of spaced openings, a leg associated with each of said openings, said leg being formed at its upper end to provide means engageable with one edge of the associated opening to provide a pivotal connection about which the leg may be swung downwardly toward a normal vertical position, said leg and said flange having vertically extending, interfitting provisions engageable by such swinging movement of the leg and co-operating when engaged to prevent move-

ment of the leg about a horizontal axis radial of the seat, and means rigidly interconnecting the lower ends of said legs.

7. In a stool or chair, a generally horizontal sheet-metal seat having a generally downwardly extending peripheral flange having a plurality of spaced openings, a leg associated with each of said openings, said leg being formed at its upper end to provide means engageable with one edge of the associated opening to provide a pivotal connection about which the leg may be swung downwardly toward a normal vertical position, said leg and said flange having below the opening vertically extending, interfitting provisions engageable by such swinging movement of the leg and co-operating when engaged to prevent movement of the leg about a horizontal axis radial of the seat, and a ring secured to the legs near the lower end thereof.

8. In a stool or chair, a generally horizontal

sheet-metal seat having a generally downwardly extending peripheral flange having a plurality of spaced openings, a leg associated with each of said openings, said leg being formed at its upper end to provide means engageable with one edge of the associated opening to provide a pivotal connection about which the leg may be swung downwardly toward a normal vertical position, said leg and said flange having below the opening vertically extending, interfitting provisions engageable by such swinging movement of the leg and co-operating when engaged to prevent movement of the leg about a horizontal axis radial of the seat, and a ring secured to the legs near the lower end thereof.
